(57) CLAIM

The ornamental design for a portable kegged beverage container, as shown and described.

DESCRIPTION

FIG. 1 is a left side view of the portable kegged beverage container showing my design;

FIG. 2 is a front view thereof;

FIG. 3 is a right side view thereof;

FIG. 4 is a rear view thereof;

FIG. 5 is a top view thereof;

FIG. 6 is a bottom view thereof;

FIG. 7 is a front perspective view thereof; and,

FIG. 8 is a rear perspective view thereof.

The broken lines in the figure drawings are included for the purpose of illustration and form no part of the claimed design.
